CIRCULAR RESTAURANT BUILDING

Spero Mihilas, Belleville, Ill.
(1862 Lake Spier Drive, Winter Park, Fla. 32789)

Filed July 25, 1969, Ser. No. 18,421

Term of patent 3½ years

Int. Cl. D25—04

U.S. Cl. D13—1

FIG. 1 is a top plan view of a circular restaurant building showing my new design;

FIG. 2 is a front elevational view thereof;

FIG. 3 is a rear elevational view thereof;

FIG. 4 is a left side elevational view thereof; and

FIG. 5 is a right side elevational view thereof.

I claim:

The ornamental design for a circular restaurant building, substantially as shown.
